SLICING APPARATUS

Application filed July 1, 1929. Serial No. 375,164.

This invention relates to slicing apparatus, which is particularly adapted for slicing vegetables which are to be dried, as for example in the preparation of potato chips.

5 The most important objects of the invention are to provide means for cutting thin slices of substantially uniform thickness and in the form of a succession of waves, and preferably to arrange these waves so that 10 they radiate from a common center, or in other words, so that each crest is along an arcuate line which is concentric with the crests of the other waves.

15 The specific construction of our improved apparatus, which in its present embodiment is particularly adapted for making potato chips, will be more particularly described in connection with the accompanying drawings, in which

20 Figure 1 is a front elevation of the apparatus with a portion of the front housing plate broken away.

Figure 2 is a vertical section on an enlarged scale taken substantially on the line 2—2 of 25 Figure 1.

Figure 3 is a detail sectional view taken on the line 3—3 of Figure 1.

Figure 4 is a detail sectional view taken on the line 4—4 of Figure 1.

30 Our invention, as used in making potato chips, is illustrated in connection with a housing or hood 6, the front side of which is closed by a cover plate 7 removably secured thereto by machine bolts or other suitable means. The rear portion of the housing 6 is extended rearwardly to form a sleeve 8 and suitable bearing members 9 are provided in the sleeve and at the center of the plate 7 for receiving a shaft 10, which is rotated 35 through the medium of a gear 11 secured to its rear end or by any other suitable means.

40 A block 12, preferably in the form of a circular disk, is secured to the shaft 10 within the housing 6 near the cover plate 7. The front face of this disk is formed with a series of concentric grooves 13 extending about the center thereof, so that a plane passing through the axis of the disk intersects the front face thereof in a line which is made up 45 of a succession of waves. One or more knife

blades 14 are secured to the front face of the disk 12, four such blades being shown in the present instance. Each blade 14 is formed with a series of waves 15 corresponding in contour to the face of a disk 12 and uniformly spaced therefrom a distance equal to the thickness of the slice to be cut. Behind the cutting edge of each blade 14, the disk 12 is formed with a slot 16 and the rear face of the cutting edge and the adjacent edge of the slot 16 are beveled so that the slice, as it is cut, will be directed through the slot 16 and will drop to the bottom of the housing 6.

55 For feeding the potatoes or other material to be sliced to the cutter, a hopper 17 is secured to the front face of the cover plate 7 and the cover plate is provided with a feed opening 18 at the rear side of the hopper. A pusher 19 is secured to a shaft 20, which is journaled in bearings 21 mounted on the upper part of the cover plate. The shaft 20 is formed at one end with a crank 22 having a handle 23 and the material is fed to the revolving cutter by the weight of the pusher 19 and crank 22 or by pressure applied through 60 the medium of the handle 23.

65 In the operation of our improved slicing apparatus it will be seen that the slices cut thereby are formed with a series of waves. These waves not only present an attractive appearance when the slice is dried, but the cut surface, curving as it does, intersects all of the pores or ducts in the potato, allowing the juice to run out freely, so that the slice 70 is easily and quickly dried and a large percentage of the starch contained in the potato collects upon the surface, where it may be collected after the chips are dried and will constitute a by-product of considerable value.

75 It is also to be noted that the grooves and ridges formed in the slice are curved along arcuate lines concentric with the axis about which the cutter revolves. These grooves and ridges act as a reinforcement in the direction of their length, and since this direction constantly changes, with different degrees of curvature for different ridges, the entire surface of the chip maintains substantially its original shape and does not curl 80 up during the drying process. This results 85

100

in a product of uniformly attractive appearance.

While we have shown and described in considerable detail the preferred form of the invention, it is to be understood that this is merely for the purpose of illustration and that the invention includes all such modifications as may fall within the scope of the appended claims.

10. What we claim is:

1. In a slicing apparatus, a cutting blade having a surface extending sinuously in the direction of its length and terminating at its front side in a continuously curved sinuous cutting edge, the crests of the waves defining a series of concentric arcs, and means for moving said blade repeatedly above the common center of said arcs and across the material to cut therefrom successive slices of substantially uniform thickness and each made up of a succession of arcuate concentric waves.

2. In a slicing apparatus, a cutting blade having a surface extending sinuously in the direction of its length and terminating at its front side in a continuously curved sinuous cutting edge, the crests of the waves defining a series of concentric arcs, a block to which said blade is secured, said block having a sinuous surface complementary to the sinuous surface of the blade and spaced therefrom, and means for moving said blade and block about the common center of said arcs, to cut slices having a series of acute concentric waves, which pass between the blade and the block.

3. In a slicing apparatus, a rotatable disk having a face formed with a series of alternate grooves and ridges concentric to its axis, and of such contour that a plane through the disk intersects them in a continuous sinuous curve, a cutting blade secured to the disk having a face spaced from the grooved face of the disk and having a contour complementary thereto, whereby slices cut by the rotation of the disk from material held thereagainst will be of wavy form, with the crests of the waves on arcuate lines concentric to the axis of the disk.

50. In testimony whereof we have hereunto signed our names to this specification.

ERNEST G. BREMFORDER.
JOSEPH WOZNIAK.
